DESIGN FOR A PLATE WHIRLER

James T. Campbell, Detroit, Mich.

Application March 22, 1944, Serial No. 113,002

Term of patent 7 years

(Cl. D61—1)

To all whom it may concern:

Be it known that I, James T. Campbell, a citizen of the United States, residing at Detroit, in the county of Wayne and State of Michigan, have invented a new, original, and ornamental Design for a Plate Whirler, for which the following is a specification, reference being had to the accompanying

drawings, forming part thereof, in which the figure is a perspective view of a plate whirler showing my new design.

I claim:

The ornamental design for a plate whirler, substantially as shown.

JAMES T. CAMPBELL.
